UNITED STATES PATENT OFFICE.

H. L. CHARLES RENAULD, OF BROOKLYN, AND MARSHALL B. STAFFORD,
OF NEW YORK, N. Y.

BOTTLE-STOPPER FASTENING.

SPECIFICATION forming part of Letters Patent No. 253,427, dated February 7, 1882.

Application filed November 2, 1881. (No model.)

To all whom it may concern:

Be it known that we, H. L. CHARLES RENAULD, of Brooklyn, Kings county, New York, and MARSHALL B. STAFFORD, of the city, county, and said State of New York, have invented a new and useful Improvement in Bottle-Stopper Fastenings, of which the following is a specification, reference being had to the accompanying drawings.

10 The invention relates to improvements in fasteners for the stoppers or covers of bottles and other vessels. It is specially applicable for use in closing the mouths of bottles containing sparkling wines or effervescent waters.

15 The object of the invention is to obviate the necessity, in a neat, economical manner, of securing corks in bottles, jugs, &c., by means of strings, wire, &c.

20 The particular nature of the invention will be understood from the detailed description hereinafter presented, reference being had to the accompanying drawings, of which—

Figure 1 is a vertical section of the upper part of a bottle having the invention applied. 25 Fig. 2 is a side elevation of the fastener detached from the bottle. Fig. 3 is a side elevation of the cap D, and Fig. 4 is a top and side view of the ring f.

30 A indicates a bottle, and B the usual cork or stopper, which will be inserted in the neck of the bottle in the customary way.

D denotes the cap or cover, of a size adapted to pass over the cork and mouth of the bottle, as illustrated in Fig. 1, and which consists of 35 a plain body inclosed at its upper end, and having at opposite sides, near its base, the vertical slots a and the horizontal slots b, the slots b leading from the upper ends of the slots a and at right angles thereto. The purpose of 40 the cap and slot will be explained hereinafter.

Upon the neck of the bottle, near its upper end, is usually provided the collar or shoulder d, and this collar we utilize in the effectuation of the objects of our invention. Below the collar d we prefer to attach or mold with the bottle the collar or shoulder e, which is a plain projection extending around the neck of the 45 bottle.

Between the collars d e we place the ring f, which is made in two sections, g h, having intermeshing ends and provided with the lugs i. By means of the sections g h, having intermeshing ends, the ring may be formed around the neck of bottles varying in size without the use of mechanical appliances and without delay. It is well known that in the manufacture 50 of bottles the exact proportions of the necks and other parts vary in some respects, and to readily adapt the ring f to these varying proportions is the purpose of constructing it in sections having ends which intermesh. The sections g h are of such size that when placed upon the neck of the bottle they will form a ring which will snugly fit the article, but at the same time be capable of an easy revolving 55 movement thereon. When the ring is formed the lugs i project outward at right angles on each side thereof.

In the employment of our invention upon champagne-bottles, after the bottle has been 60 filled the cork is inserted in the usual manner and the ring f applied, after which the plunger of the bottling-machine (if a machine is used) is raised from the cork and the cap or cover D inserted over the mouth of the bottle 65 and pressure again applied, the slots a in the lower edge of the cap slipping down over the lugs i. The cap is locked in this position by turning the ring f so that its lugs i will enter the horizontal slots b. When the parts are in 70 this position the pressure of the gas within the bottle forces the cork against the cap D, which, by drawing on the lugs i, prevents the ring f from turning easily, and thus the whole is locked in place. The bottle may be opened 75 by simply turning the ring f until its lugs i come opposite to the slots a, when the cap may be removed by hand or will be blown away by the gas contained in the wine.

It should be particularly noted that in securing the cap upon the bottle the ring f, not at that time having any strain upon it, may be turned by the thumb and finger easily and without force. Thus the cork may be fastened without loss of time and without unusual effort. 95

What we claim as our invention, and desire to secure by Letters Patent, is—

The fastening herein described for securing the stopper in bottles and other vessels, consisting of the cap D, adapted to pass over the stopper and mouth of the vessel, and provided at its lower portion with the slots a b, in combination with the ring f, composed of sections g h, having intermeshing ends and carrying the lugs i, the ring being applied on the neck of the vessel to turn and cause the lugs to lock or free the cap, substantially as set forth.

In testimony that we claim the foregoing improvement in bottle-stopper fastenings, as above described, we have hereunto set our hands this 28th day of October, 1881.

H. L. CHAS. RENAUD.
MARSHALL B. STAFFORD.
